UNITED STATES PATENT OFFICE.

SERGIUS BESSONOFF, OF ST. PETERSBURG, RUSSIA.

WATER-LEVEL REGULATOR.

SPECIFICATION forming part of Letters Patent No. 440,218, dated November 11, 1890.

Application filed June 4, 1890. Serial No. 354,291. (No model.) Patented in Belgium April 12, 1890, No. 90,174; in France April 12, 1890, No. 204,968, and in Germany April 15, 1890, No. 53,684.

To all whom it may concern:

Be it known that I, SERGIUS BESSONOFF, a subject of the Emperor of Russia, residing in St. Petersburg, Russia, have invented certain new and useful Improvements in Water-Level Regulators, (for which I have obtained Letters Patent in the following countries: in Belgium April 12, 1890, No. 90,174; in Germany April 15, 1890, No. 53,684, and in France April 12, 1890, No. 204,968;) and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is an elevation of my improved feed-water regulator for steam-boilers, showing the boiler in vertical transverse section and the regulating-cylinder in vertical longitudinal section. Fig. 2 is a vertical longitudinal section, and Fig. 3 an end elevation, of the regulating-cylinder. Figs. 4, 5, and 6 are vertical longitudinal sections of the regulating-cylinder, illustrating various modifications in the means for regulating the pressures on opposite sides of the piston; and Fig. 7 is a detail view.

My invention has for its object to provide means for automatically controlling the supply of water fed to the boiler, and for automatically maintaining the supply of water within the boiler at a normal or approximately normal level to avoid the danger of explosion due to "low water" in the boiler—that is to say, to an insufficiency of water in the boiler and to the sudden development of steam by the contact of a volume of water with an abnormally large area of the heated boiler-shell.

To these ends my invention consists in the improvement of and means for automatically controlling the volume of a fluid supplied to a receiver by a pump through the medium of the fluid in said receiver being made to antagonize the movements of the pump-piston and by varying the antagonizing force exerted by the fluid upon the pump-piston, according to the variations in the pressure or level of said fluid within its receiver, as will

now be more fully described, reference being had to the accompanying drawings, in which like letters indicate like parts, and more particularly to Figs. 1, 2 and 3 thereof.

55

B indicates a steam-boiler; P, a pump, and E the engine-cylinder that operates the pump, all of which may be of well-known and usual construction. The regulator consists, essentially, of an auxiliary pump adapted to operate with the boiler, water or steam, or both, antagonistically to the pumping-engine.

60 C indicates the piston-cylinder of the auxiliary pump, and hereinafter called the "regulator-cylinder," whose piston-rod R is rigidly connected with the piston-rod of the pump in any desired manner—as, for instance, by the yoke Y, Fig. 1.

65 In the head H of the regulator C is formed a passage h, in which is seated a gravity-valve V, 70 that opens inwardly, and to the said passage h is connected a pipe p, that extends into the boiler to a point but slightly above the normal water-line. In the same head H of the regulator is formed a second passage h', provided with a seat for a ball-valve V', that opens outwardly, the throw of which valve is adjustable by means of the abutment a at the end of the screw-rod r, that works in a suitable interiorly-threaded bearing c, passes 75 through a suitable stuffing-box and gland, and carries at its outer end a hand-wheel W. In the head H' of the regulator C are likewise formed two passages h² h³, the latter passage h³ being connected by pipe p³ with 80 the passage h' above the ball-valve V', and to the passage h² is connected a pipe p², that extends into the steam-space of the boiler B.

85 It will readily be seen that so long as the water in the boiler is at a normal level steam 90 alone will be drawn into the regulator-cylinder whatever the direction of motion of its piston P'. During the suction-stroke of the piston, steam will be drawn in through pipe p, valve V moving off its seat, while during 95 the forcing-stroke of said piston, steam will be drawn in through pipe p², the steam on the opposite side of the piston being forced through passage h', the valve V' moving off its seat through pipe p³ and passage h³ to the right of the piston P', and thence back to the boiler against the steam-pressure therein.

- So long as the steam alone enters the regulator-cylinder there is comparatively little resistance to the movements of the piston P' , and consequently to the movements of the pump-piston. When, however, the level of the water rises to such a height that water is drawn in through pipe p , the resistance to the movements of the regulator-piston P' is increased, thereby retarding or checking the movements of the pump-piston and reducing the supply of water to the boiler, according to the resistance opposed to the movements of the regulator-piston P' . The resistance to the movements of the last-named piston and the equalizing of such resistance to the said movements in either direction may be effected in various ways—as, for instance, by adjusting the throw of the ball-valve V' , Figs. 1 and 2.
- According to the level of the water in the boiler, steam or water, or both, will be drawn into the regulating-cylinder C. On the return or forcing stroke of the piston steam will be drawn into the cylinder through pipe p^2 on the right side of the piston, the fluid on the left side being forced over. Now if the valve V' is properly adjusted the combined fluids on the right of the piston will offer the same resistance to the movements of the piston on its next suction-stroke as did the fluid previously drawn in, as will be readily understood. The same results may be attained and the valves V and V' dispensed with by reducing the cross-sectional area of the connecting-pipe p^3 and passage h^3 relatively to the admission-pipe p , as shown in Fig. 4, where the connecting-pipe p^3 is shown as connected directly with the inlet-pipe p , the cross-sectional area of said pipe p^3 relatively to said pipe p being such as to convey a volume of fluid that when combined with steam drawn in through pipe p^2 will offer the same resistance to the movement of the piston as the fluid drawn in through pipe p , a portion of which fluid will be forced back into the boiler during the forcing-stroke of the piston P' through the passage h^3 , pipe p^3 , and suction-pipe p .
- The arrangement shown in Fig. 5 varies from those shown in Figs. 1, 2, and 4, in that a portion of the fluid is also forced back to the boiler, as in the construction shown in Fig. 4, through the admission or suction pipe p , a passage h^4 being here formed around the seat S of the ball-valve V' , and said valve is made sufficiently heavy, so that it will not be moved off its seat so long as steam only or but a small volume of water combined with steam is drawn into the regulator-cylinder C. At each forcing-stroke of the piston P' the resistance to its movement is controlled by the pressure in the boiler and the cross-sectional area of the passages $h' h^3$ and connecting-pipe p^3 , a portion of the fluid in the regulator-cylinder being forced back into the boiler and the remainder into the opposite end of the cylinder through passages $h' h^3$ and pipe p^3 , steam being simultaneously drawn into the

same end of the cylinder through pipe p^2 , the resistance of which fluids to the return or suction stroke of the piston P' being equal to that of the fluid contained in the cylinder during the forcing-stroke. A like result may be obtained by connecting the exhaust-pipe p^2 with the feed-water pipe and interposing a check-valve V^2 in said connection in conjunction with the valves V V' , said check-valve interrupting the inflow of feed-water into the regulator-cylinder C, as shown in Fig. 6, and in this case the cross-sectional area of the passage h^2 and exhaust-pipe p^2 relatively to the cross-sectional area of the inlet-pipe p , passages $h' h^3$, and connecting-pipe p^3 serve to equalize the resistance to the movements of the piston.

To avoid the choking or obstructing of the connections between the regulator and boiler from solid matter floating upon the water in the boiler, I prefer to provide the pipe p with a strainer of any desired form—such, for instance, as a rose-head D, Fig. 1.

In the drawings I have shown the pipes p and p^2 entering the boiler from below; but it will be understood that this is not absolutely necessary, as either or both pipes may project into the boiler from above; nor is it material at what particular point of the boiler the said pipes are located. In marine boilers it will, however, be found necessary to introduce the pipes from above and at a point about midway of the boiler, in order to avoid the level variations due to the rolling and pitching of a vessel. In this case I provide the suction-pipe p with an inverted-bell-shaped guard G, Fig. 7, to prevent solid matter floating on the boiler-water from entering said pipe. The guard G is so arranged on the pipe as to project some distance beyond its inlet, and therefore dips to a considerable depth into water, thus preventing access of solid matter to the pipe p , the guard being provided with perforations g in its top, the object of which will be readily understood.

I do not desire to limit myself to the precise arrangement of the connections between the boiler and regulator as shown and described, as these may be modified according to the relative location of the boiler and the pump and according to other conditions of use of the boiler; nor do I desire to limit myself to the construction of the valves V V' V^2 , as various other forms of valves may be employed, or to the means for connecting the piston-rod of the regulator with that of the pump, as any suitable connection other than that shown may be provided.

I have described and illustrated my improved feed-water regulator in its application to a steam-boiler; but it will be obvious that the regulator may be applied to various other apparatus for controlling the volume of a fluid supplied by a pump or pumping-engine.

Having described my invention, what I claim, and desire to secure by Letters Patent, is—

1. As an improvement in the art of controlling the volume of a fluid supplied by a pump to a receiver, which consists in controlling the movements of the pump-piston through the medium of the fluid in the receiver by causing such fluid to antagonize the movements of said pump-piston, as set forth.

2. As an improvement in the art of controlling the volume of a fluid supplied by a pump to a receiver, which consists in controlling the movements of the pump-piston through the medium of the fluid in the receiver by causing such fluid to antagonize the movements of the pump-piston and varying the action of the fluid upon said piston according to the variations in the pressure of the fluid in the receiver, as set forth.

3. As an improvement in the art of controlling the volume of a fluid supplied by a pump to a receiver, which consists in controlling the movements of the pump-piston through the medium of the fluid in the receiver by causing such fluid to antagonize the movements of the pump-piston and varying the action of the fluid upon said piston according to the variations in the level of the fluid in the receiver, as set forth.

4. A regulator for controlling the volume of a fluid supplied to a receiver by a pump, comprising a supply-pump, a regulating or controlling pump the suction and forcing ports whereof are in communication with the receiver, and a connection between the pistons of the two pumps, substantially as and for the purpose specified.

5. A regulator for controlling the volume of a fluid supplied to a receiver by a pump, comprising a supply-pump, a receiver or vessel for the fluid supplied by said pump, a regulating or controlling pump, a duct extending from the suction - port of said controlling-pump into the receiver to about the line of normal level, a duct extending from the exhaust-port of the controlling-pump into the receiver to a point above the line of normal level of the fluid therein, and a connection between the pistons of both pumps, substantially as and for the purpose specified.

6. A regulator for controlling the volume of a fluid supplied to a receiver by a pump, comprising a supply-pump, a receiver or vessel for the fluid supplied by said pump, a regulating or controlling pump, a duct extending

from the suction-port of the latter pump into the receiver to about the line of normal level of the fluid therein, a valve opening inwardly for said suction-port, a connection between the suction and exhaust ends of the cylinder of said controlling-pump, an adjustable valve in said connection, a duct extending from the exhaust-port of the controlling-pump into the receiver above the line of normal level of the fluid therein, and a connection between the pistons of both pumps, substantially as and for the purpose specified.

7. A regulator for controlling the volume of a fluid supplied to a receiver by a pump, comprising a supply-pump, a receiver or vessel for the fluid supplied by said pump, a regulating or controlling pump, a duct extending from the suction-port of the latter pump into the receiver to about the line of normal level of the fluid therein, a valve for said port opening inwardly, a duct in communication with the suction and exhaust ends of the controlling-pump cylinder and with the receiver through the suction-duct, a duct extending from the exhaust - port of the controlling-pump into the receiver above the line of normal level of the fluid therein, and a connection between the pistons of the two pumps, substantially as and for the purpose specified.

8. In a regulator for controlling the volume of a fluid supplied to a receiver by a pump, the combination, with the supply-pump, the receiver for the fluid supplied by said pump, and the controlling-pump cylinder C, of the suction-pipe p, extending into said receiver, and a strainer for the inlet end of said pipe, substantially as and for the purpose specified.

9. In a regulator for controlling the volume of a fluid supplied to a receiver by a pump, the combination, with the supply-pump, the receiver for the fluid supplied by said pump, and the controlling-pump cylinder C, of the suction-pipe p, extending into said receiver, and the bell-shaped guard G, provided in its end wall with perforations g, substantially as and for the purpose specified.

In testimony whereof I have signed my name to this specification in the presence of two subscribing witnesses.

SERGIUS BESSONOFF.
